UNITED STATES PATENT OFFICE.

GATES H. BARNARD, OF NEW YORK, N. Y.

DESIGN FOR A COLLAR.

SPECIFICATION forming part of Design No. 18,539, dated August 21, 1888.

Application filed July 30, 1888. Serial No. 281,479. Term of patent 7 years.

To all whom it may concern:

Be it known that I, GATES H. BARNARD, of the city, county, and State of New York, have invented a new, useful, and original Design 5 for Collars; and I do hereby declare that the following is a full and exact description thereof, reference being had to the accompanying drawings, and to the letters of reference marked thereon, making a part of this specification, 10 in which—

Figure 1 is a plan view of a collar opened out, showing my design for its outline; Fig. 2, a cross-section of same in line x x of Fig. 1; and Fig. 3, a view in perspective, on an enlarged scale, of the collar in shape for wear.

A represents the extended strip which constitutes the collar. The outline of the lower edge, B, of this strip has the form of an extended inward curve, which is slightly reversed as it approaches either end, as shown at C C. The outline of its upper edge is irregular, being made to follow centrally for about two-thirds its length substantially a straight line, D, parallel with an imaginary straight line drawn between the extremities of the lower edge, B, (see dotted line E, Fig. 1,) and to form by means of offsets F F an obtuse angle at each end with said straight upper edge, D, and with lines G G extending from the inner end, H, of the offset to the extremities K K of the strip, which lines G G

slope inwardly from said ends K to said inner end or angle, H, of the offsets. The ends K K of the strip are preferably inclined at an angle more or less acute with the straight line E connecting the extremities of its lower edge, B. The wider portion D B of the strip, included between the offsets F F, is bent transversely, so that the upper portion inclines at an obtuse angle with the lower portion, as shown in Figs. 2 and 3.

What I claim is—

The design for a standing collar herein shown and described, which consists in the shape imparted to an extended strip or collar 45 of irregular width, whereby the collar is in form narrower at its ends than in the center, angular in transverse section at its wide part, inwardly curved upon its lower edge, and with offsets in its upper edge at either end, forming 50 an obtuse angle both with a right line defining said upper edge between the offsets and with the lines which incline inwardly from the ends of the collar to the inner angles of the offsets and define the margin between them. 55

In testimony whereof I have signed my name to this specification in the presence of two subscribing witnesses.

GATES H. BARNARD.
